(57) **ABSTRACT**

The invention provides a GOA driving circuit, comprising: a plurality of GOA units connected in cascade, each GOA unit comprising a pull-up control module (1), a pull-up module (2), a pull-down module (3), a first pull-down maintenance module (4), and a second pull-down maintenance module (5); on the basis of ensuring the normal function of the GOA unit, the pull-down module (3) uses one less TFT than the prior art, the first pull-down maintenance module (4) uses one less TFT than the prior art, the second pull-down maintenance module (5) uses one less TFT than the prior art, thereby saving the wiring area used by GOA driving circuit and facilitating the narrow border LCD. The invention provides an LCD using the GOA driving circuit. Therefore, the number of the TFTs of the GOA driving circuit is less, the wiring area is smaller, and the LCD border is narrower.

GOA DRIVING CIRCUIT AND LCD

BACKGROUND OF THE INVENTION

1. Field of the Invention

The present invention relates to the field of display techniques, and in particular to a GOA driving circuit and LCD.

2. The Related Arts

The liquid crystal display (LCD), or LCD panel, provides the advantages of thinness, power-saving, no radiation, and so on, and is widely applied to, such as, liquid crystal TV, smart phone, digital camera, tablet PC, PC monitor, or notebook PC, and stays as a leading technology in panel display.

The operation principle behind the LCD is to pour liquid crystal (LC) molecules between the thin film transistor (TFT) array substrate and the color filter (CF) substrate, and then apply a driving voltage to the two substrates to control the rotation direction of the LC molecules to refract the light of the backlight module r to produce the image.

The LCD has a plurality of pixels arranged in an array, with each pixel electrically connected to a TFT, the gate of the TFT T connected to a horizontal scan line, the source connected to the vertical data line, and the drain connected to the pixel electrode. Applying the gate scan signal Gate to the scan line 100 will cause all the TFTs T connected to the scan line 100 to turn on. Then, applying the data signal Data to the data line 200 will be able to write into corresponding sub-pixel to control the LC transmittance to achieve color and brightness control. Gate-driver-on-Array (GOA) uses the existing TFT array process to fabricate integratedly the gate scan driving circuit on the TFT array to achieve driving the gates. Replacing the conventional gate driver IC with GOA has the potential to improve yield rate and reduce cost, as well as making the LCD more suitable for narrow-border or borderless display products.

FIG. 1 shows a known GOA driving circuit, comprising: a plurality of cascade GOA units, each GOA unit comprising a pull-up control module 100, a pull-up module 200, a pull-down module 300, a first pull-down maintenance module 400, a second pull-down maintenance module 500, and a bootstrap capacitor 600, electrically connected to a first node Q(n) and a second node P(n).

For an integer n, in n-th GOA unit, the pull-up module 200 is mainly responsible for outputting the x-th high-frequency clock signal C (x) in the inputted high-frequency clock signal set to the corresponding scanning line as the scan driving signal G(n), while outputting the cascade-propagate signal ST(n).

The pull-up control module 100 is connected to receive the scan driving signal G(n-6) and the cascade-propagate signal ST(n-6) outputted from the (n-6)th GOA unit to control the turn-on of the pull-up module 200.

The pull-down module 300 comprises two TFTs T31 and T41, wherein: T31 is connected to the scan driving signal G(n+6) outputted from the (n+6)th GOA unit and the DC low voltage VSS, and is responsible for quickly pulling the scan driving signal G(n) and the second node P(n) down to low voltage after the scanning driving signal G(n) outputting high voltage; T41 is connected to the scan driving signal G(n+6) outputted from the (n+6)th GOA unit and the DC low voltage VSS, is responsible for quickly pulling the first

node Q (n) to low voltage after the scan driving signal G(n) outputting a high voltage, turning off the pull-up module 200.

The first pull-down maintenance module 400 is connected to the first low-frequency clock signal LC1 and the DC low-voltage VSS, and the second pull-down maintenance module 500 is connected to the second low-frequency clock signal LC2 and the DC low-voltage VSS, and the two operate alternatingly so that the first node Q(n) and the second node P(n) are kept at a low voltage; wherein the first pull-down maintenance module 400 comprises six TFTs: T51, T52, T53, T54, T32, and T42, and the second pull-down maintenance module 500 comprises six TFTs: T61, T62, T63, T64, T33, and T43.

The shortcomings of the existing GOA driving circuit are that the number of TFTs is large and requires a larger wiring area, disadvantageous to the narrow border trend of LCD.

SUMMARY OF THE INVENTION

The object of the present invention is to provide a GOA driving circuit, able to reduce the number of TFTs and save GOA wiring area to enable border narrowing of LCD.

Another object of the present invention is to provide an LCD with a GOA driving circuit, able to reduce the number of TFTs and save GOA wiring area to enable border narrowing of LCD.

To achieve the above object, the present invention provides a GOA driving circuit, which comprises: a plurality of cascade GOA units, with each GOA unit comprising a pull-up control module, a pull-up module, a pull-down module, a first pull-down maintenance module, and a second pull-down maintenance module;

for integers n and x, in the n-th GOA unit:

the pull-up control module being electrically connected to a first node, for controlling the pull-up module to turn on;

the pull-up module being electrically connected to the first node and a second node, for receiving a x-th high-frequency clock signal in a high-frequency clock signal set, and outputting high voltage of the x-th high-frequency clock signal to corresponding scan line as a scan driving signal, outputting a cascade-propagate signal, and pulling down voltage levels of the scan driving signal and the second node after the scan driving signal outputting high voltage;

the pull-down module only comprising a 41st thin film transistor (TFT), the 41st TFT having a source electrically connected to the first node, a drain connected to a direct current (DC) low voltage, for pulling down voltage level of the first node after the scan driving signal outputting;

the first pull-down maintenance module comprising: a 51st TFT, a 52nd TFT, a 53rd TFT, a 32nd TFT, and a 42nd TFT; the 51st TFT having a gate and a source receiving a first low-frequency clock signal, and a drain electrically connected to a third node; the 53rd TFT having a gate electrically connected to the third node, a source receiving the first low-frequency clock signal, and a drain electrically connected to the third node; the 52nd TFT having a gate electrically connected to the first node, a source connected to the third node, and a drain receiving a DC low voltage; the 32nd TFT having a gate electrically connected to the third node, a source electrically connected to the second node, and a drain receiving DC low voltage; the 42nd TFT having a gate electrically connected to the third node, a source electrically connected to the first node, and a drain receiving the DC low voltage;

the second pull-down maintenance module comprising: a 61st TFT, a 62nd TFT, a 63rd TFT, a 33rd TFT, and a 43rd TFT;

the 61st TFT having a gate and a source receiving a second low-frequency clock signal, and a drain electrically connected to a fourth node; the 63rd TFT having a gate electrically connected to the fourth node, a source receiving the second low-frequency clock signal, and a drain electrically connected to the fourth node; the 62nd TFT having a gate electrically connected to the first node, a source connected to the fourth node, and a drain receiving a DC low voltage; the 33rd TFT having a gate electrically connected to the fourth node, a source electrically connected to the second node, and a drain receiving DC low voltage; the 43rd TFT having a gate electrically connected to the fourth node, a source electrically connected to the first node, and a drain receiving the DC low voltage;

the first pull-down maintenance module and the second pull-down maintenance module operating alternately to maintain the voltage level of the scan driving signal, the second node, and the first node at low voltage after pulled down.

According to a preferred embodiment of the present invention, the GOA driving circuit further comprises a bootstrap capacitor, with two electrode plates electrically connected to the first node and the second node respectively.

According to a preferred embodiment of the present invention, the pull-up control module comprises an 11th TFT;

assuming m is an integer less than n, except the first GOA unit to the m-th GOA unit, in the n-th GOA unit, the 11th TFT has a gate receiving a cascade-propagate signal outputted from (n-m)th GOA unit, a source receiving a scan driving signal outputted from (n-m)th GOA unit, and a drain electrically connected to the first node;

except the last GOA unit to the last m-th GOA unit, in the n-th GOA unit, the 41st TFT has a gate receiving a cascade-propagate signal outputted from (n+m)th GOA unit.

According to a preferred embodiment of the present invention, the pull-up module comprises a 21st TFT and a 22nd TFT;

the 21st TFT has a gate electrically connected to the first node, a source receiving an x-th high-frequency clock signal in a high-frequency clock signal set, and a drain electrically connected to the second node and outputting the scan driving signal of the n-th GOA unit;

the 22nd TFT has a gate electrically connected to the first node, a source receiving an x-th high-frequency clock signal in a high-frequency clock signal set, and a drain outputting the cascade-propagate signal of the n-th GOA unit.

According to a preferred embodiment of the present invention, in the first GOA unit to the m-th GOA unit, the 11th TFT has a gate receiving an STV signal and a source receiving the STV signal;

in the last GOA unit to the last m-th GOA unit, the 41st TFT has a gate receiving the STV signal.

According to a preferred embodiment of the present invention, m is set to 6.

According to a preferred embodiment of the present invention, the first low-frequency clock signal and the second low-frequency clock signal have opposite phase.

According to a preferred embodiment of the present invention, the high-frequency clock signal set comprises 12 high-frequency clock signals; with every 12 GOA units as a repetition unit, the 12 GOA units of a repetition unit receive the first to 12th high-frequency clock signal sequentially.

According to a preferred embodiment of the present invention, the STV signal has a rising edge generated prior to the rising edge of the first high-frequency clock signal,

and the STV signal has a falling edge generated simultaneously with falling edge of the first high-frequency clock signal.

The present invention also provides an LCD, which comprises the aforementioned GOA driving circuit.

The present invention also provides a GOA driving circuit, which comprises: a plurality of cascade GOA units, with each GOA unit comprising a pull-up control module, a pull-up module, a pull-down module, a first pull-down maintenance module, and a second pull-down maintenance module;

for integers n and x, in the n-th GOA unit:

the pull-up control module being electrically connected to a first node, for controlling the pull-up module to turn on;

the pull-up module being electrically connected to the first node and a second node, for receiving a x-th high-frequency clock signal in a high-frequency clock signal set, and outputting high voltage of the x-th high-frequency clock signal to corresponding scan line as a scan driving signal, outputting a cascade-propagate signal, and pulling down voltage levels of the scan driving signal and the second node after the scan driving signal outputting high voltage;

the pull-down module only comprising a 41st thin film transistor (TFT), the 41st TFT having a source electrically connected to the first node, a drain connected to a direct current (DC) low voltage, for pulling down voltage level of the first node after the scan driving signal outputting;

the first pull-down maintenance module comprising: a 51st TFT, a 52nd TFT, a 53rd TFT, a 32nd TFT, and a 42nd TFT; the 51st TFT having a gate and a source receiving a first low-frequency clock signal, and a drain electrically connected to a third node; the 53rd TFT having a gate electrically connected to the third node, a source receiving the first low-frequency clock signal, and a drain electrically connected to the third node; the 52nd TFT having a gate electrically connected to the first node, a source connected to the third node, and a drain receiving a DC low voltage; the 32nd TFT having a gate electrically connected to the third node, a source electrically connected to the second node, and a drain receiving DC low voltage; the 42nd TFT having a gate electrically connected to the third node, a source electrically connected to the first node, and a drain receiving the DC low voltage;

the second pull-down maintenance module comprising: a 61st TFT, a 62nd TFT, a 63rd TFT, a 33rd TFT, and a 43rd TFT; the 61st TFT having a gate and a source receiving a second low-frequency clock signal, and a drain electrically connected to a fourth node; the 63rd TFT having a gate electrically connected to the fourth node, a source receiving the second low-frequency clock signal, and a drain electrically connected to the fourth node; the 62nd TFT having a gate electrically connected to the first node, a source connected to the fourth node, and a drain receiving a DC low voltage; the 33rd TFT having a gate electrically connected to the second node, and a drain receiving DC low voltage; the 43rd TFT having a gate electrically connected to the fourth node, a source electrically connected to the first node, and a drain receiving the DC low voltage;

the first pull-down maintenance module and the second pull-down maintenance module operating alternately to maintain the voltage level of the scan driving signal, the second node, and the first node at low voltage after pulled down;

further comprising a bootstrap capacitor, with two electrode plates electrically connected to the first node and the second node respectively;

wherein the pull-up control module comprising an 11th TFT;

assuming m is an integer less than n, except the first GOA unit to the m-th GOA unit, in the n-th GOA unit, the 11th TFT having a gate receiving a cascade-propagate signal outputted from (n-m)th GOA unit, a source receiving a scan driving signal outputted from (n-m)th GOA unit, and a drain electrically connected to the first node;

except the last GOA unit to the last m-th GOA unit, in the n-th GOA unit, the 41st TFT having a gate receiving a cascade-propagate signal outputted from (n+m)th GOA unit;

wherein the pull-up module comprising a 21st TFT and a 22nd TFT;

the 21st TFT having a gate electrically connected to the first node, a source receiving an x-th high-frequency clock signal in a high-frequency clock signal set, and a drain electrically connected to the second node and outputting the scan driving signal of the n-th GOA unit;

the 22nd TFT having a gate electrically connected to the first node, a source receiving an x-th high-frequency clock signal in a high-frequency clock signal set, and a drain outputting the cascade-propagate signal of the n-th GOA unit;

wherein in the first GOA unit to the m-th GOA unit, the 11th TFT having a gate receiving an STV signal and a source receiving the STV signal;

in the last GOA unit to the last m-th GOA unit, the 41st TFT having a gate receiving the STV signal.

The present invention provides the following advantages: the invention provides a GOA driving circuit, comprising: a plurality of GOA units connected in cascade, each GOA unit comprising a pull-up control module, a pull-up module, a pull-down module, a first pull-down maintenance module, and a second pull-down maintenance module; on the basis of ensuring the normal function of the GOA unit, the pull-down module uses one less TFT than the prior art, the first pull-down maintenance module uses one less TFT than the prior art, the second pull-down maintenance module uses one less TFT than the prior art, thereby saving the wiring area used by GOA driving circuit and facilitating the narrow border LCD. The invention provides an LCD using the GOA driving circuit. Therefore, the number of the TFTs of the GOA driving circuit is less, the wiring area is smaller, and the LCD border is narrower.

BRIEF DESCRIPTION OF THE DRAWINGS

To make the technical solution of the embodiments according to the present invention, a brief description of the drawings that are necessary for the illustration of the embodiments will be given as follows. Apparently, the drawings described below show only example embodiments of the present invention and for those having ordinary skills in the art, other drawings may be easily obtained from these drawings without paying any creative effort. In the drawings:

FIG. 1 is a schematic view showing a known circuit of the n-th GOA unit of the GOA driving circuit;

FIG. 2 is a schematic view showing a circuit of the n-th GOA unit of the GOA driving circuit of the present invention;

FIG. 3 is a schematic view showing the timing sequence of each driving signal of the GOA driving circuit of the present invention;

FIG. 4 is a schematic view showing the timing sequence of each scan driving signal outputted by the GOA driving circuit of the present invention.

DETAILED DESCRIPTION OF THE PREFERRED EMBODIMENTS

Referring to FIG. 2, FIG. 3 and FIG. 4 simultaneously, the present invention provides a GOA driving circuit, comprising: a plurality of cascade GOA units, with each GOA unit comprising a pull-up control module 1, a pull-up module 2, a pull-down module 3, a first pull-down maintenance module 4, a second pull-down maintenance module 5, and a bootstrap capacitor 6.

The pull-up control module 1 is for controlling the pull-up module 2 to turn on. Specifically, the pull-up control module 1 comprises an 11th TFT T11. For an integer m, m< n, except the first GOA unit to the m-th GOA unit, in the n-th GOA unit, the 11th TFT T11 has a gate receiving a cascade-propagate signal ST(n-m) outputted from (n-m)th GOA unit, a source receiving a scan driving signal G(n-m) outputted from (n-m)th GOA unit, and a drain electrically connected to the first node Q(n); in the first GOA unit to the m-th GOA unit, the 11th TFT has a gate receiving a synchronous activation signal, usually referred to as an STV signal, of a frame of image, and a source receiving the STV signal. Take m=6 as an example. In the 1st to 6th GOA units, the 11th TFT T11 has a gate receiving an STV signal and a source receiving the STV signal. In the 7th to last GOA units, the 11th TFT T11 has a gate receiving a cascade-propagate signal ST(n-6) outputted from (n-6)th GOA unit, a source receiving a scan driving signal G(n-6) outputted from (n-6)th GOA unit.

The pull-up module 2 is electrically connected to the first node Q(n) and a second node P(n), for receiving a x-th high-frequency clock signal CK(x) in a high-frequency clock signal set, x being an integer, and outputting high voltage of the x-th high-frequency clock signal CK(x) to corresponding scan line as a scan driving signal G(n), outputting a cascade-propagate signal ST(n), and pulling down voltage levels of the scan driving signal G(n) and the second node P(n) after the scan driving signal G(n) outputting high voltage. Specifically, the pull-up module 2 comprises a 21st TFT T21 and a 22nd TFT T22. The 21st TFT T21 has a gate electrically connected to the first node Q(n), a source receiving an x-th high-frequency clock signal CK(x) in a high-frequency clock signal set, and a drain electrically connected to the second node P(n) and outputting the scan driving signal G(n) of the n-th GOA unit. When the x-th high-frequency clock signal CK(x) is at high voltage, the scan driving signal G(n) outputted from the 21st TFT T21 is also at high voltage; when the x-th high-frequency clock signal CK(x) changes to the low voltage, the scan driving signal G(n) outputted from the 21st TFT T21 follows the CK(x), i.e., is pulled down to low voltage. The 22nd TFT T22 has a gate electrically connected to the first node Q(n), a source receiving an x-th high-frequency clock signal CK(x) in a high-frequency clock signal set, and a drain outputting the cascade-propagate ST(n) of the n-th GOA unit.

The pull-down module 3 only comprises a 41st TFT T41, except the last GOA unit to the last m-th GOA unit, in the n-th GOA unit, the 41st TFT T41 has a gate receiving a cascade-propagate signal G(n+m) outputted from (n+m)th GOA unit, a source electrically connected to the first node Q(n), a drain connected to a direct current (DC) low voltage VSS. In the last GOA unit to the last m-th GOA unit, the 41st TFT T41 has a gate receiving the STV signal. Take m=6 as

an example. In the last GOA unit to the last 6th GOA unit, the 41st TFT T41 has a gate receiving the STV signal. In the 1st to the last 7th GOA units, the 41st TFT T41 has a gate receiving a cascade-propagate signal G(n+6) outputted from (n+6)th GOA unit. The pull-down module 3 only uses the 41st TFT T41 to lower the voltage level of the first node Q(n) after the output of the scan driving signal G(n). Compared to the existing GOA circuits in FIG. 1, the 31st TFT T31 for pulling down the voltage level of the scan driving signal G(n) and the second node P(n) is eliminated, and the task is completed by the 21st TFT T21 in the pull-up module 2.

The first pull-down maintenance module 4 comprises: a 51st TFT T51, a 52nd TFT T52, a 53rd TFT T53, a 32nd TFT T32, and a 42nd TFT T42; the 51st TFT T51 has a gate and a source receiving a first low-frequency clock signal LC1, and a drain electrically connected to a third node S(n); the 53rd TFT T53 has a gate electrically connected to the third node S(n), a source receiving the first low-frequency clock signal LC1, and a drain electrically connected to the third node S(n); the 52nd TFT T52 has a gate electrically connected to the first node Q(n), a source connected to the third node S(n), and a drain receiving a DC low voltage VSS; the 32nd TFT T32 has a gate electrically connected to the third node S(n), a source electrically connected to the second node P(n), and a drain receiving DC low voltage VSS; the 42nd TFT T42 has a gate electrically connected to the third node S(n), a source electrically connected to the first node Q(n), and a drain receiving the DC low voltage VSS. When the first low-frequency clock signal LC1 is at high voltage and the first node Q(n) is at low voltage, the 51st TFT T51 and the 53rd TFT T53 are turned on and the 52nd TFT T52 is cut-off. The high voltage of the first low-frequency clock signal LC1 reaches the third node S(n) and controls the 32nd TFT T32 to turn on so that the second node P(n) continues to conduct the DC low voltage VSS. The 42nd TFT T42 is turned on so that the first node Q(n) continues to conduct the DC low voltage VSS. Compared to the existing GOA circuit in FIG. 1, the first pull-down maintenance module 4 eliminates the 54th TFT T54 on the basis of ensuring the pull-down maintenance function operating normally.

The second pull-down maintenance module 5 comprises: a 61st TFT T61, a 62nd TFT T62, a 63rd TFT T63, a 33rd TFT T33, and a 43rd TFT T43; the 61st TFT T61 has a gate and a source receiving a second low-frequency clock signal LC2, and a drain electrically connected to a fourth node K(n); the 63rd TFT T63 has a gate electrically connected to the fourth node K(n), a source receiving the second low-frequency clock signal LC2, and a drain electrically connected to the fourth node K(n); the 62nd TFT T62 has a gate electrically connected to the first node Q(n), a source connected to the fourth node K(n), and a drain receiving a DC low voltage VSS; the 33rd TFT T33 has a gate electrically connected to the fourth node K(n), a source electrically connected to the second node P(n), and a drain receiving DC low voltage VSS; the 43rd TFT T43 has a gate electrically connected to the fourth node K(n), a source electrically connected to the first node Q(n), and a drain receiving the DC low voltage VSS. When the second low-frequency clock signal LC2 is at high voltage and the first node Q(n) is at low voltage, the 61st TFT T61 and the 63rd TFT T63 are turned on and the 22nd TFT T22 is cut-off. The high voltage of the second low-frequency clock signal LC2 reaches the fourth node K(n) and controls the 33rd TFT T33 to turn on so that the second node P(n) continues to conduct the DC low voltage VSS. The 43rd TFT T43 is turned on so that the first node Q(n) continues to conduct the DC low voltage VSS. Compared to the existing GOA circuit in FIG. 1, the second pull-down

maintenance module 5 eliminates the 64th TFT T64 on the basis of ensuring the pull-down maintenance function operating normally.

The bootstrap capacitor 6 has two electrode plates electrically connected to the first node Q(n) and the second node P(n) respectively. The bootstrap capacitor 6 is for pulling the voltage level of the first node Q(n) when scan driving signal G(n) outputted by the 21st TFT T21 is at high voltage.

Furthermore, as shown in FIG. 3, the first low-frequency 10 clock signal and the second low-frequency clocks signal have opposite phase, to control the first pull-down maintenance module 4 and the second pull-down maintenance module 5 operating alternatingly to maintain the voltage level of the scan driving signal G(n), the second node P(n), and the first node Q(n) at low voltage after pulled down. The high-frequency clock signal set comprises 12 high-frequency clock signals; with every 12 GOA units as a repetition unit, the 12 GOA units of a repetition unit receive the 15 first to 12th high-frequency clock signal CK(1)-CK(12) sequentially. The STV signal has a rising edge generated 20 prior to the rising edge of the first high-frequency clock signal CK(1), and the STV signal has a falling edge generated simultaneously with falling edge of the first high-frequency clock signal CK(1).

25 The operation of the n-th GOA unit of the GOA driving circuit of the present invention is described as follows:

First phase: the cascade-propagate signal ST(n-6) and the 30 scan driving signal G(n-6) outputted by the (n-6)th GOA unit are both at high voltage, the 11th TFT T11 is turned on (the 11th TFT T11 of the 1st to 6th GOA units are all turned on under the control of the SRV signal, to charge the bootstrap capacitor 6. The first node Q(n) is at high voltage to control the 21st TFT T21 and 22nd TFT T22 to turn on, the 50 52nd TFT T52 and the 62nd TFT T62 are turned on, the DC low voltage VSS reaches the third node S(n) and the fourth node K(n). The 32nd TFT T32, the 42nd TFT T42, the 33rd TFT T33 and the 43rd TFT T43 are all cut-off.

Second phase: the x-th high-frequency clock signal CK(x) 40 provides high voltage, the 21st TFT T21 outputs high voltage scan driving signal G(n), the 22nd TFT T22 outputs the high voltage cascade-propagate signal ST(n), the bootstrap capacitor 6 raises the first node Q(n) even higher voltage level, the second node P(n) is at high voltage, the 32nd TFT T32, the 42nd TFT T42, the 33rd TFT T33 and the 43rd TFT T43 are all still cut-off.

Third phase: the x-th high-frequency clock signal CK(x) becomes low voltage, the scan driving signal G(n) outputted 50 from the 21st TFT T21 is pulled to low voltage; the high voltage scan driving signal G(n+6) outputted by the (n+6)th GOA unit arrives to control the 41st TFT T41 to turn on (the last to the last 6th GOA units control the turn-on of the 41st TFT T41 through STV signal) so that the first node Q(n) conducts the DC low voltage VSS, and pull down the voltage level of the first node Q(n).

55 Fourth Phase: the 52nd TFT T52 and the 62nd TFT T62 are cut off by the low voltage of the first node Q(n), the first low-frequency clock signal LC1 and the second low-frequency clock signal LC2 provide high voltage alternatingly. Correspondingly, the first pull-down maintenance module 4 and the second pull-down maintenance module 5 operate 60 alternatingly so maintain the voltage level of the scan driving signal G(n), the second node P(n), and the first node Q(n) at low voltage after pulled down.

As shown in FIG. 4, GOA driving circuit outputs, in a 65 stage-by-stage manner, scan driving signals G(1), G(2), G(3), G(4), G(5), G(6), G(7), and G(8). The operation is normal and stable. Compared to the prior art, the pull-down

module 3 uses one less TFT, the first pull-down maintenance module 4 uses one less TFT and the second pull-down maintenance module 5 uses one less TFT. The GOA driving circuit of the present invention reduces the number of TFTs, saves the wiring area of the GOA driving circuit and enables narrow border LCD.

Based on the same design, the present invention also provides an LCD, comprising the above GOA driving circuit. Hence, the GOA driving circuit of the present invention reduces the number of TFTs, saves the wiring area of the GOA driving circuit and enables narrow border LCD. The details will not be repeated here.

In summary, the invention provides a GOA driving circuit, comprising: a plurality of GOA units connected in cascade, each GOA unit comprising a pull-up control module, a pull-up module, a pull-down module, a first pull-down maintenance module, and a second pull-down maintenance module; on the basis of ensuring the normal function of the GOA unit, the pull-down module uses one less TFT than the prior art, the first pull-down maintenance module uses one less TFT than the prior art, the second pull-down maintenance module uses one less TFT than the prior art, thereby saving the wiring area used by GOA driving circuit and facilitating the narrow border LCD. The invention provides an LCD using the GOA driving circuit. Therefore, the number of the TFTs of the GOA driving circuit is less, the wiring area is smaller, and the LCD border is narrower.

It should be noted that in the present disclosure the terms, such as, first, second are only for distinguishing an entity or operation from another entity or operation, and does not imply any specific relation or order between the entities or operations. Also, the terms "comprises", "include", and other similar variations, do not exclude the inclusion of other non-listed elements. Without further restrictions, the expression "comprises a . . ." does not exclude other identical elements from presence besides the listed elements.

Embodiments of the present invention have been described, but not intending to impose any unduly constraint to the appended claims. Any modification of equivalent structure or equivalent process made according to the disclosure and drawings of the present invention, or any application thereof, directly or indirectly, to other related fields of technique, is considered encompassed in the scope of protection defined by the claims of the present invention.

What is claimed is:

1. A gate-driver-on-array (GOA) driving circuit, which comprises: a plurality of cascade GOA units, with each GOA unit comprising a pull-up control module, a pull-up module, a pull-down module, a first pull-down maintenance module, and a second pull-down maintenance module; for integers n and x, in the n-th GOA unit: the pull-up control module being electrically connected to a first node, for controlling the pull-up module to turn on; the pull-up module being electrically connected to the first node and a second node, for receiving a x-th high-frequency clock signal in a high-frequency clock signal set, and outputting high voltage of the x-th high-frequency clock signal to corresponding scan line as a scan driving signal, outputting a cascade-propagate signal, and pulling down voltage levels of the scan driving signal and the second node after the scan driving signal outputting high voltage; the pull-down module only comprising a 41st thin film transistor (TFT), the 41st TFT having a source electrically connected to the first node, a drain connected to

a direct current (DC) low voltage, for pulling down voltage level of the first node after the scan driving signal outputting;

the first pull-down maintenance module comprising: a 51st TFT, a 52nd TFT, a 53rd TFT, a 32nd TFT, and a 42nd TFT; the 51st TFT having a gate and a source receiving a first low-frequency clock signal, and a drain electrically connected to a third node; the 53rd TFT having a gate electrically connected to the third node, a source receiving the first low-frequency clock signal, and a drain electrically connected to the third node; the 52nd TFT having a gate electrically connected to the first node, a source connected to the third node, and a drain receiving a DC low voltage; the 32nd TFT having a gate electrically connected to the third node, a source electrically connected to the second node, and a drain receiving DC low voltage; the 42nd TFT having a gate electrically connected to the third node, a source electrically connected to the first node, and a drain receiving the DC low voltage;

the second pull-down maintenance module comprising: a 61st TFT, a 62nd TFT, a 63rd TFT, a 33rd TFT, and a 43rd TFT; the 61st TFT having a gate and a source receiving a second low-frequency clock signal, and a drain electrically connected to a fourth node; the 63rd TFT having a gate electrically connected to the fourth node, a source receiving the second low-frequency clock signal, and a drain electrically connected to the fourth node; the 62nd TFT having a gate electrically connected to the first node, a source connected to the fourth node, and a drain receiving a DC low voltage; the 33rd TFT having a gate electrically connected to the fourth node, a source electrically connected to the second node, and a drain receiving DC low voltage; the 43rd TFT having a gate electrically connected to the fourth node, a source electrically connected to the first node, and a drain receiving the DC low voltage;

the first pull-down maintenance module and the second pull-down maintenance module operating alternatingly to maintain the voltage level of the scan driving signal, the second node, and the first node at low voltage after pulled down.

2. The GOA driving circuit as claimed in claim 1, wherein the GOA driving circuit further comprises a bootstrap capacitor, with two electrode plates electrically connected to the first node and the second node respectively.

3. The GOA driving circuit as claimed in claim 1, wherein the pull-up control module comprises an 11th TFT;

assuming m is an *integer* less than n, except the first GOA unit to the m-th GOA unit, in the n-th GOA unit, the 11th TFT has a gate receiving a cascade-propagate signal outputted from (n-m)th GOA unit, a source receiving a scan driving signal outputted from (n-m)th GOA unit, and a drain electrically connected to the first node;

except the last GOA unit to the last m-th GOA unit, in the n-th GOA unit, the 41st TFT has a gate receiving a cascade-propagate signal outputted from (n+m)th GOA unit.

4. The GOA driving circuit as claimed in claim 3, wherein in the first GOA unit to the m-th GOA unit, the 11th TFT has a gate receiving an STV signal and a source receiving the STV signal;

in the last GOA unit to the last m-th GOA unit, the 41st TFT has a gate receiving the STV signal.

5. The GOA driving circuit as claimed in claim 4, wherein m is set to 6.

11

6. The GOA driving circuit as claimed in claim 5, wherein the high-frequency clock signal set comprises 12 high-frequency clock signals; with every 12 GOA units as a repetition unit, the 12 GOA units of a repetition unit receive the first to 12th high-frequency clock signal sequentially.

7. The GOA driving circuit as claimed in claim 6, wherein the STV signal has a rising edge generated prior to the rising edge of the first high-frequency clock signal, and the STV signal has a falling edge generated simultaneously with falling edge of the first high-frequency clock signal.

8. The GOA driving circuit as claimed in claim 1, wherein the pull-up module comprises a 21st TFT and a 22nd TFT; the 21st TFT has a gate electrically connected to the first

node, a source receiving an x-th high-frequency clock signal in a high-frequency clock signal set, and a drain electrically connected to the second node and outputting the scan driving signal of the n-th GOA unit; the 22nd TFT has a gate electrically connected to the first node, a source receiving an x-th high-frequency clock signal in a high-frequency clock signal set, and a drain outputting the cascade-propagate signal of the n-th GOA unit.

9. The GOA driving circuit as claimed in claim 1, wherein the first low-frequency clock signal and the second low-frequency clock signal have opposite phase.

10. A liquid crystal display (LCD), comprising a GOA driving circuit as claimed in claim 1.

11. A gate-driver-on-array (GOA) driving circuit, which comprises: a plurality of cascade GOA units, with each GOA unit comprising a pull-up control module, a pull-up module, a pull-down module, a first pull-down maintenance module, and a second pull-down maintenance module;

for integers n and x, in the n-th GOA unit: the pull-up control module being electrically connected to a first node, for controlling the pull-up module to turn on;

the pull-up module being electrically connected to the first node and a second node, for receiving a x-th high-frequency clock signal in a high-frequency clock signal set, and outputting high voltage of the x-th high-frequency clock signal to corresponding scan line as a scan driving signal, outputting a cascade-propagate signal, and pulling down voltage levels of the scan driving signal and the second node after the scan driving signal outputting high voltage;

the pull-down module only comprising a 41st thin film transistor (TFT), the 41st TFT having a source electrically connected to the first node, a drain connected to a direct current (DC) low voltage, for pulling down voltage level of the first node after the scan driving signal outputting;

the first pull-down maintenance module comprising: a 51st TFT, a 52nd TFT, a 53rd TFT, a 32nd TFT, and a 42nd TFT; the 51st TFT having a gate and a source receiving a first low-frequency clock signal, and a drain electrically connected to a third node; the 53rd TFT having a gate electrically connected to the third node, a source receiving the first low-frequency clock signal, and a drain electrically connected to the third node; the 52nd TFT having a gate electrically connected to the first node, a source connected to the third node, and a drain receiving a DC low voltage; the 32nd TFT having a gate electrically connected to the third node, a source electrically connected to the second node, and a drain receiving DC low voltage; the 42nd TFT having a gate

electrically connected to the third node, a source electrically connected to the first node, and a drain receiving the DC low voltage;

the second pull-down maintenance module comprising: a 61st TFT, a 62nd TFT, a 63rd TFT, a 33rd TFT, and a 43rd TFT; the 61st TFT having a gate and a source receiving a second low-frequency clock signal, and a drain electrically connected to a fourth node; the 63rd TFT having a gate electrically connected to the fourth node, a source receiving the second low-frequency clock signal, and a drain electrically connected to the fourth node; the 62nd TFT having a gate electrically connected to the first node, a source connected to the fourth node, and a drain receiving DC low voltage; the 33rd TFT having a gate electrically connected to the fourth node, a source electrically connected to the first node, and a drain receiving the DC low voltage;

the first pull-down maintenance module and the second pull-down maintenance module operating alternatingly to maintain the voltage level of the scan driving signal, the second node, and the first node at low voltage after pulled down;

further comprising a bootstrap capacitor, with two electrode plates electrically connected to the first node and the second node respectively;

wherein the pull-up control module comprising an 11th TFT;

assuming m being an integer less than n, except the first GOA unit to the m-th GOA unit, in the n-th GOA unit, the 11th TFT having a gate receiving a cascade-propagate signal outputted from (n-m)th GOA unit, a source receiving a scan driving signal outputted from (n-m)th GOA unit, and a drain electrically connected to the first node;

except the last GOA unit to the last m-th GOA unit, in the n-th GOA unit, the 41st TFT having a gate receiving a cascade-propagate signal outputted from (n+m)th GOA unit;

wherein the pull-up module comprising a 21st TFT and a 22nd TFT;

the 21st TFT having a gate electrically connected to the first node, a source receiving an x-th high-frequency clock signal in a high-frequency clock signal set, and a drain electrically connected to the second node and outputting the scan driving signal of the n-th GOA unit; the 22nd TFT having a gate electrically connected to the first node, a source receiving an x-th high-frequency clock signal in a high-frequency clock signal set, and a drain outputting the cascade-propagate signal of the n-th GOA unit;

wherein in the first GOA unit to the m-th GOA unit, the 11th TFT having a gate receiving an STV signal and a source receiving the STV signal;

in the last GOA unit to the last m-th GOA unit, the 41st TFT having a gate receiving the STV signal.

12. The GOA driving circuit as claimed in claim 11, wherein m is set to 6.

13. The GOA driving circuit as claimed in claim 12, wherein the high-frequency clock signal set comprises 12 high-frequency clock signals; with every 12 GOA units as a repetition unit, the 12 GOA units of a repetition unit receive the first to 12th high-frequency clock signal sequentially.

14. The GOA driving circuit as claimed in claim 13, wherein the STV signal has a rising edge generated prior to

the rising edge of the first high-frequency clock signal, and the SW signal has a falling edge generated simultaneously with falling edge of the first high-frequency clock signal.

15. The GOA driving circuit as claimed in claim **11**, wherein the first low-frequency clock signal and the second low-frequency clocks signal have opposite phase. 5
